DESIGN FOR A TRANSPARENT COMB OR SIMILAR ARTICLE

Joseph Brunetti, Carlstadt, N. J., assignor to
Columbia Protektosite Co., Inc., Carlstadt, N. J.,
a corporation of New Jersey

Application October 16, 1945, Serial No. 122,900

Term of patent 7 years

(Cl. D86—8)

To all whom it may concern:

Be it known that I, Joseph Brunetti, a citizen of the United States and resident of Carlstadt, in the county of Bergen and State of New Jersey, have invented a new, original, and ornamental Design for a Transparent Comb or Similar Article, of which the following is a specification, reference being had to the accompanying drawing, forming a part thereof, and of which Figure 1 is a side view of a transparent comb or similar article showing my new design; Fig. 2 is a similar view of the opposite side thereof; Fig. 3 is a

top view thereof; Fig. 4 is an end view thereof on a slightly smaller scale; and Fig. 5 is an enlarged sectional view of the same on line 5—5 of Fig. 1.

The dominant features of the design reside in the portions shown in full lines.

I claim:

The ornamental design for a transparent comb or similar article, substantially as shown and described.

JOSEPH BRUNETTI.
